UNITED STATES PATENT OFFICE.

THOMAS FERGUSON, OF LOWELL, MASSACHUSETTS, ASSIGNOR, BY MESNE ASSIGNMENTS, TO DRAPER CORPORATION, OF HOPEDALE, MASSACHUSETTS, A CORPORATION OF MAINE.

FEELER DEVICE FOR FILLING-REPLENISHING LOOMS.

1,308,234.

Specification of Letters Patent.

Patented July 1, 1919.

Application filed November 24, 1914. Serial No. 873,824.

To all whom it may concern:

Be it known that I, THOMAS FERGUSON, a subject of King George V of Great Britain, residing at Lowell, county of Middlesex, 5 and State of Massachusetts, have invented an Improvement in Feeler Devices for Filling-Replenishing Looms, of which the following description, in connection with the accompanying drawings, is a specification, 10 like characters on the drawings representing like parts.

This invention relates to filling replenishing looms wherein the filling is replenished when required; and more particularly it is 15 directed to means for detecting and indicating substantial exhaustion of the filling in the running shuttle and on the occurrence thereof to cause a change in the loom operation, such as automatic replenishment of the 20 filling.

In the prior patent of Charles F. Roper, No. 821,123, dated May 22, 1906, there was shown, described, and claimed, a device of the above general character comprising two 25 members movable relatively, one member being adapted to penetrate or sink into the filling mass and the other to impinge against it, to cause differential movement of said members on each beat-up of the lay so long 30 as a working supply of filling was present in the shuttle, and on the occurrence of substantial exhaustion of the filling, to move in unison and initiate filling replenishment. These characteristic movements of the penetrat- 35 ing and impinging members were dependent upon the difference in density or hardness of the filling mass and the bobbin on which it was wound, the said penetrating and impinging members being normally in 40 position with the impinging surface of the impinging member and the end of the penetrating member in alinement, so that upon contact of the feeler device with a working supply of filling as the lay beats up, the impinging member was moved relatively or 45 differentially to the penetrating member to inoperatively position filling replenishing controlling means, but upon substantial exhaustion of filling, the two members were 50 moved in unison and effected by such simultaneous movement, an initiation of filling replenishment.

The present invention is a development of that of the Roper patent mentioned, and

its aim is to provide a mechanical feeler device, wherein a penetrating member will be normally positioned with its penetrating portion beyond the impinging face of an impinging member, so that while a working supply of filling is present in the shuttle, 55 the penetrating member will first be met by the mass of filling as the lay beats up, sink into the same, and then the impinging member will engage the filling mass and both of said members be then moved in unison or 60 simultaneously without initiating filling replenishment; but upon substantial exhaustion of filling, the penetrating member will first engage the more dense or hard surface 65 of the bobbin or carrier, and be moved relatively or differentially with respect to the impinging member, to initiate filling re- 70 replenishment. These characteristics of the invention will best be made clear from the following more detailed description and accompanying drawings of a good, practical 75 form of the present invention.

In the drawings:

Figure 1 is a plan view of a feeler device embodying a form of the present invention 80 and showing sufficient of a shuttle-box, shuttle, and filling carrier, to make clear the association and operation of the invention:

Fig. 2 is a section on the line 2—2, Fig. 1, some of the parts being shown in elevation; 85

Fig. 3 is a plan view similar to that of Fig. 1, but showing the filling in a condition of substantial exhaustion;

Fig. 4 is a section on line 4—4, Fig. 3; and

Fig. 5 is a detached view of the penetrat- 90 ing member of the feeler.

The shuttle S has an opening 1 in its side wall, adapted to register with an opening 2 in the front wall of the shuttle-box 3 at the detecting side of the loom when the 95 shuttle S is properly boxed on the detecting pick, said openings 1 and 2 providing for the entrance of the feeler device into the shuttle, substantially as fully set forth by the Roper patent hereinbefore-mentioned. 100

Mounted in position to enter the openings 1 and 2 in the shuttle-box wall and shuttle, to detect the condition of the filling in the shuttle, is the feeler device, comprising a penetrating member to penetrate or sink 105 into the relatively soft mass of working filling, and an impinging member to contact with the said mass following the penetration

of the penetrating member into said filling, the result being that when a working supply of filling is present in the shuttle, the relation of the penetrating member and impinging member remains substantially the same as before when the lay beats up, but when the filling has become practically exhausted, the penetrating member contacts with the more dense substance of the bobbin and is moved relatively or differentially to the impinging member whereupon filling replenishment is initiated, as will more fully appear.

As a good, practical form of the invention, the drawings show a suitable support or stand 4 adapted to be secured to a fixed part of the loom by suitable means, such as the screws 5, 5, and having mounted thereon for movement toward and from the front of the loom the feeler slide, preferably, though not of necessity, formed of the two side members 6, 6. The feeler slide is guided in its movements by the stand or support 4, and to this end said support has a chambered portion 7, into which the side members extend, said members being connected within the chambered portion 7 by the cross-piece 8, Figs. 1, 2, and 4, carrying a stem 9. Surrounding the stem 9 and acting normally to maintain the feeler slide in rear position as indicated, is a spring 10, one end of which bears against the cross-piece 8 and the other end upon the end wall of the chamber 7. The support or stand 4 is preferably formed of a base portion and cover detachably connected by the screws 5, a shoulder 11 on the interior of the cover serving as a limiting stop for determining the rearward limit of slide movement under the impulse of the spring 10, as indicated.

Extending longitudinally of the support or stand 4 is a piece 12 forming a guide slot 13 for an arm 14 for initiating filling replenishment when said arm is moved by the feeler, as will presently appear. The arm 14 constitutes a controller for controlling the operative condition of parts for initiating the filling replenishing operation, and while it is herein shown as extending into the guide slot 13 and adapted to be moved longitudinally in said slot, it is to be understood that the controller may be of any character which, upon movement induced by detection of filling exhaustion, will initiate the replenishing operation or position the parts for that purpose.

The slide members 6, 6, are connected at the rear or at the left, Figs. 1 and 3, by a head 15 constituting the impinging member of the feeler device and having an impinging surface 16 extending longitudinally of the filling carrier against the filling on which it is adapted to impinge as the lay beats up following a detecting pick.

Normally extending beyond the imping-

ing surface of the impinging member, is the penetrating portion of the penetrating member, which may be variously formed and designed, but in the particular form of the invention illustrated, is constituted by the two points 17, 17, carried by the penetrating member 18. As a good, practicable form of the penetrating member, it is shown as an angular plate 18 having a part 19 carrying the penetrating points 17 and mounted for sliding movement on the impinging member. To this end the impinging member 15 is suitably slotted, as shown, to accommodate the part 19 with capacity for free sliding movement.

Pivottally mounted on the feeler slide by means of the pin 20 is a finger 21 having an end portion 22 adapted, under conditions to be described, to move the controller 14. The part 23 of the finger is provided with a lug 24 for the reception of an adjustable piece 25 conveniently formed as a screw passing through said lug 24 and tapped into the arm 26 of the finger. A lock nut 27 serves to lock the screw in adjusted position. The adjustable piece or screw 25 is provided with an end portion 28 against which the upright portion 29 of the penetrating member 18 is adapted to bear, substantially as shown.

The finger 21 is preferably disposed intermediate the side portions 6, 6, of the feeler slide, though this is not essential, and is normally maintained with its end portion 22 in raised position, Fig. 2, by suitable yielding means, such as the pin 30 guided for rectilinear movement in suitable bearings 31 of the stand or support 4. A spring 32 interposed between a collar 33 on said pin and the stand or support 4 normally acts to hold said pin in position with the end 22 of the finger raised, and the part 28 of the screw bearing against the upright portion 29 of the penetrating member 18, and normally maintains the penetrating portions 17, 17 of the penetrating member in position projecting beyond the impinging surface 16 of the impinging member 15. When the parts are in the position described, the upright portion 29 of the penetrating member contacts with the edge of the slotted impinging member and limits the amount of projection of the penetrating portions 17 of the penetrating member beyond the impinging surface 16 of the impinging member, as will be readily understood.

From the construction described as a good, practical form or embodiment of the present invention, it will be seen that the penetrating portion of the penetrating member normally projects beyond the impinging surface of the impinging member, and that when a sufficient supply of filling is present in the shuttle for working purposes, the penetrating portion of the penetrating member will first engage the mass of filling in the

shuttle as the lay moves forward and sink thereinto, and upon further forward movement of the lay, the impinging member will meet the mass of filling and the two members will thereupon maintain their established relation and move in unison toward the front of the loom, without initiating filling replenishment. When, however, the filling has become practically exhausted, the 10 penetrating portion of the penetrating member will again be met by the filling as the lay moves forward, but will now strike the more dense substance of the filling carrier or bobbin and be by it moved relatively or 15 differentially to the impinging member, thereby acting through the finger to lower the free end thereof into position to engage the controller, so that, on further forward movement of the lay, the controller will be 20 moved to change the operative condition of the loom or initiate filling replenishment. The association and relation of parts hereinbefore described as constituting a good, practical form of the invention, may be variously modified, the essential being that the 25 penetrating and impinging members shall be so related that the penetrating member will first be met by the filling on the forward movement of the lay, and sink into 30 the filling when a proper working supply is present, without disturbing the established relation between the penetrating and impinging members; but when the filling has become practically exhausted, that the penetrating member will be relatively or differentially moved with respect to the impinging member to effect initiation of filling 35 replenishment.

What is claimed is:—

40 1. A feeler mechanism for looms, comprising in combination, an impinging member and a penetrating member, the former having an extended impinging surface, the penetrating member having two penetrating 45 points separated a distance less than the

length of and between the ends of the impinging surface of the impinging member and normally projecting beyond the impinging surface of the impinging member and adapted to sink into the filling before 50 the impinging surface engages the filling when a working supply is presented opposite either of the penetrating portions, so that relative movement of the impinging and penetrating members on a detecting beat 55 will be effected only when the filling is substantially exhausted opposite both penetrating points of the penetrating member.

2. In a feeler motion for looms, the combination of an impinging member having an impinging surface extending longitudinally of the shuttle and adapted to engage and be moved forwardly by the filling when a working supply is presented to any portion of the impinging surface on a detecting 60 beat, a penetrating member having two rigidly joined penetrating portions normally projected beyond the impinging surface of the impinging member between the end limits thereof and adapted to engage the filling 65 in the shuttle on a detecting beat at two positions separated longitudinally of the shuttle a distance less than the length of the impinging surface and to sink into the filling before the impinging surface engages 70 the filling when a working supply is presented opposite either of the penetrating portions, and means actuated only when the filling is substantially exhausted opposite 75 both of said penetrating portions of the 80 penetrating member for initiating filling replenishment.

In testimony whereof, I have signed my name to this specification, in the presence of two subscribing witnesses.

THOMAS FERGUSON.
